UNITED STATES PATENT OFFICE.

GEORGE B. CLAY, OF JENKINTOWN, PENNSYLVANIA.

HOSE-COUPING.

946,935.

Specification of Letters Patent. Patented Jan. 18, 1910.

Application filed August 9, 1909. Serial No. 512,099.

To all whom it may concern:

Be it known that I, GEORGE B. CLAY, a citizen of the United States, residing at Jenkintown, in the county of Montgomery and State of Pennsylvania, have invented certain new and useful Improvements in Hose-Couplings, of which the following is a specification, reference being had therein to the accompanying drawing.

10 My invention relates to couplings, and is in the nature of an improvement in what are known as Clay-Jones hose couplings in common use in municipal fire departments and elsewhere. The characteristic feature 15 of such couplings is a pair of side jaws or clamps on one member which engage an annular flange on the other. Heretofore a small pick has been employed for opening these jaws in uncoupling, and it has been 20 suggested to use a lever construction. Neither of these expedients is satisfactory in practice however, the former because it involves the use of a separate part which is particularly liable to be lost or mislaid, and the 25 latter because a lever is liable to become clogged with mud and ice in winter and thereby to become absolutely inoperative.

According to the present invention, I shape the jaws in a peculiar manner, by extending the side metal so that they can be 30 opened by means of a variety of tools; the shape being such that there is no danger of clogging or freezing under any conditions, and in the absence of tools the fingers will 35 suffice.

My invention is illustrated in the accompanying drawings in which—

Figure 1 is a side view of a complete Clay-Jones coupling embodying my invention. 40 Fig. 2 is a face view of one jaw detached. Fig. 3 is a side view of the same. Fig. 4 is a plan view thereof.

Referring to the drawings and particularly to Fig. 1, A is one member of the coupling, and B is the other. The member A has a flange *a* within which an annular seat is provided for the bearing face *b* of the member B. Above this bearing face an annular groove *b'* is formed, leaving a projecting edge or flange *b''*, which when the members are joined, is engaged by the edges *c* of the jaws C. These jaws or clamps are normally held in operative position, with their upper ends pressed forward, by means 55 of phosphor bronze springs, and when necessary to open them, what is known as a "hose

pick" or "key" has usually been employed, which would have to be carried by every person liable to require its use.

The sides of the jaws have heretofore been 60 cast plain, since any projections form lodging places for mud and ice, besides being subject to breakage. I have found, however, that by extending the metal on each side of a jaw as shown at *c'*, and curving 65 the outer surface in a way I shall presently describe, the efficiency of the device is practically unaffected either indoors or outdoors, and the use of a hose pick is rendered unnecessary, since the fingers can be inserted under the ears thus formed, which give a sufficient grip for hand pressure to open the couplings, even when under a considerable head.

Referring particularly to Figs. 2, 3 and 4, 75 in which a single jaw clamp C is shown detached, *c²* is the axis of the pivot on which the jaw turns. This pivot consists of a screw passing through cheek plates or lugs cast on the body of the coupling member A. 80 The metal around it is disposed so as to afford ample strength to resist the strains encountered in practice and a tail piece is provided for the springs above referred to. Above the pivot line the body *c³* extends in 85 a carefully designed curve, terminating in the plane surface *c⁴*, the edge of which at *c⁵* is curved to accommodate the peripheral curve of the member B. Above this edge the metal is thickened at *c⁶*, as the tendency 90 to fracture is greatest at this point, but it will be noted that the outlines are long and gradual curves and apart from the edge *c*, all sharp edges and corners are carefully avoided. The fact that all outside surfaces on 95 this jaw are smooth curves will be evident from inspection of Fig. 2 in particular.

According to my present invention, I extend the metal on both sides of the jaw as 100 shown at *c'*. The outline of this extension is on a long outward curve from the pivot point, as shown at *c¹⁰* in Fig. 2, and then on a short reverse curve as shown at *c²⁰*. This curve is not only symmetrical in itself, but merges into the body and this idea is further carried out in the shape of the back of each projection, which is formed of compound curves so that the surface merges in all directions into that of the body. The inner face of each projection is made straight 105 in cross section, to afford a proper grip for the fingers or other instrument.

Having thus described my invention, what I claim and desire to secure by Letters Patent is—

1. In a hose coupling, a pair of coupling members, and a coupling jaw pivoted on one member so as to engage a coacting element on the other member, said jaw having all exposed surfaces formed in smooth curves, with the metal extended on both sides to form 10 overhanging grips with curved backs, substantially as described.

2. A hose coupling composed of two cooperating members, with a seat in one member and a bearing face on the other, a pair 15 of integral lugs on each side of the first

member, and a pair of jaws, one pivoted in each pair of lugs, the second member of the coupling having an annular flange adapted for engagement by the extremity of said jaws, each jaw having an underlying spring 20 to force it into such engagement, and each jaw also having curved extensions on each side forming grips for disengaging, all substantially as described.

In testimony whereof I affix my signature 25 in presence of two witnesses.

GEORGE B. CLAY.
